UNITED STATES PATENT OFFICE.

HUGH W. SANFORD, OF KNOXVILLE, TENNESSEE.

MINE-CAR COUPLING.

Application filed March 22, 1922, Serial No. 546,050. Renewed June 23, 1925.

To all whom it may concern:

Be it known that I, HUGH W. SANFORD, a citizen of the United States, residing at Knoxville, in the county of Knox and State of Tennessee, have invented a new and useful Improvement in Mine-Car Couplings, of which the following is a specification, reference being had to the accompanying drawing.

My improvement relates particularly to coupling mechanism designed for the automatic coupling of mine cars used on rail tracks which are unevenly supported and which have frequent and irregular curves and frequent changes in grade.

The object of the invention is to provide a simple coupling structure which will become engaged automatically when cars are pushed endwise against each other under the varying conditions mentioned above and which coupling structure will remain in engagement during pushing and pulling and jolting of the cars at varying velocity on such irregular trackage as I have above indicated.

A further object of the improvement is to provide such a coupling structure in a form which will permit disengagement of the coupling structures of adjoining cars and putting said structures into such position as to permit the turning of one of the cars parallel to the length of the car without interference of the coupling or bumper element of one car with the coupling or bumper elements of the adjoining car or cars, this arrangement allowing a train of such cars to be moved progressively through a rotary tipple, the car or cars at the time in the tipple being turned by the tipple for dumping, until all the cars have been thus emptied, and the cars being adapted to automatic recoupling by pushing or bumping the cars against each other.

In the accompanying drawings,

Fig. 1 is a plan showing ends of cars provided with my improved coupling and bumper structure;

Fig. 2 is a horizontal section on the line, 2-2, of Fig. 1;

Fig. 3 is an upright section on the line, 3-3, of Figs. 1 and 2, looking in the direction of the arrow;

Fig. 4 is an upright section on the line, 4-4, of Figs. 1 and 2, looking in the direction of the arrow.

Referring to said drawings, A, A design-

nate the end sill at the end of a mine car which bears the bumper which is to be engaged by a hook on the adjoining bumper; and A¹, A¹ designate the end sill bearing a bumper and said hook. B, B designate the bumper to be engaged by the hook. C, C designate the bumper with which is associated a hook, C¹. On one end of each car is a bumper, B, while on the other end of the same car is a bumper, C, and a hook, C¹, combined with the bumper, C. It is intended that the cars shall be placed in trains with all the bumpers, B, or all the bumpers, C, directed toward the front of the train, so that throughout the train bumpers, B, and C, will be opposite each other.

Each bumper, B, has in its upper face a recess, B¹, extending near enough to the convex face of the bumper to leave an outer upright wall, B². The bottom of said recess is a floor, B³, in which are openings, B⁴, through which particles of mineral may fall. This is intended to prevent the filling of said recess with mineral to such extent as to prevent the hook, C¹, from engaging in said recess.

The hook, C¹, is hinged in the bumper, C, said bumper being chambered to receive the hub end of the hook.

The chamber is formed by walls, C², which are upright and at opposite sides of and equi-distant from the upright, longitudinal plane of the car and extend from the front wall, C³, of the bumper rearward. The inner part of the hook, the part which is in said chamber, has flat side faces which bear against the side walls of said chamber. At its inner end, the hook has a hub, C⁴, in which is a bearing, C⁵, of polygonal cross section. In alignment with said bearing each of the side walls of said chamber has a corresponding polygonal bearing, C⁶. A rock shaft, D, extends through said bearings. One end of said shaft merely projects through the adjacent bumper wall, C², and there receives a cross pin, D¹. At the opposite side of the bumper, said shaft extends through a bearing, D², supported on the car. At the side of said bearing opposite the bumper, a cross pin, D³, extends through said shaft to prevent movement of the shaft toward the bumper. Near said bearing said shaft is bent upward to form an arm, D⁴, which is brought to an edge at D⁵, to adapt it to engage a toothed rack, D⁶, supported on the car. For convenience and

100

105

110

economy in manufacture, this rock shaft is made of a cylindrical rod formed or cut to produce an edge at D^5 , and having the part which is in the hub, C^5 , made polygonal in cross section to fit the bearing in said hub. Thus the rock shaft, D, is held for rocking in the bearings, C^6 , and D^2 , and the hook is joined to the rock-shaft for turning in unison with said rock-shaft. The rock-shaft and the hub of the hook are placed in the inner part of the chamber, C^2 —the part toward the body of the car. Thus space is left in the chamber between said hub and the front wall, C^3 , of the bumper, C. On each upright side face of said chamber is a lug, C^7 , which forms a bearing for the adjacent face of the hub, C^5 . Said two bearings resist movement of the hub toward the wall, C^4 , when strain is put on said hook by the adjacent bumper, B. This means for staying the hook is in addition to the support given to said hub by the rock-shaft, D.

It is also to be observed that lateral support is given to the hook by the side faces of the walls, C^2 . This lateral support is important, because it tends to avoid twisting strains on the shaft, D, and compels maintaining the outer end of the hook in the upright, middle, longitudinal plane of the car regardless of the relative shifting of the bumper when the cars are on curves. By this means, the outer end of the hook is compelled to shift its engagement on the adjacent bumper, B, when the cars are put out of alignment on a curved track or one car shifts sidewise relative to the other on a straight track.

The outer end of the hook has a head, C^8 , which has a point, C^9 , directed obliquely downward and toward the hub, C^4 . The floor, B^3 , of the bumper, B, is a little below the plane of the axis of the hub, C^4 , said plane being indicated on the drawing by the line, $a-a$. The point, C^9 , of the hook is long enough to permit said point to rest on the upper face of the floor, B^3 , while the body of the hook is above and clear of the upper edge of the upright wall, B^2 , of the bumper. The distance of the floor, B^3 , below said plane is such as to cause the point of the hook to engage the wall, B^2 , in said plane.

When the hook is in this position, the bumper and coupling structures are in engagement with each other and the two cars are coupled to each other. When the train of cars is being pulled, the hook, C^1 , is under tension, the line of strain being in said plane, $a-a$. The point, C^9 , of the hook is far enough from the hub to allow the hook to be engaged when there is space between the two bumpers, in order that the two cars may be moved toward each other to free the point of the hook from the wall, B^2 , when it is desired to raise the hook out of en-

gagement with the bumper, B. The outer, upright face of the wall, B^2 , is made convex on an upright line, as above stated, and also on a center which is in said plane, $a-a$. Hence when the cars are pushed toward each other, the bumpers will meet and engage each other in the plane, $a-a$. Thus when the cars are on a track which is of substantially uniform grade and the train is being pulled, all the engagements and strains are in the plane, $a-a$; and when the train is being pushed all the bumper engagements and strains throughout the length of the train are in said plane.

When the cars are moving on a straight track and enter upon a curve and the bumpers on two cars bear against each other, during the movement on the curve, the meeting faces of said bumpers will roll upon each other in a manner similar to the rolling of the rockers of a rocking chair on a floor, the hook, C^1 , shifting horizontally in the recess, B^1 . When the train enters upon such a curve while the train is being pulled, so that the hook is under tension, the adjacent bumpers move sidewise toward the same side of the track, the hook slipping laterally along the inner face of the wall, B^2 . When the cars again enter on a straight track, the bumpers and the hooks return horizontally into their normal positions.

When the hook is to be turned up out of its working position, the cars are to be pushed together to make enough slack to free the hook from the wall, B^2 . Then the rock-shaft is to be turned to bring the hook into the upright position shown by dotted lines in Fig. 2, the arm, D^4 , engaging the rack, D^6 .

Now the hook is entirely out of the range of the bumper, B, and either car may be turned sidewise or on its longitudinal axis without being interfered with by the other car. Thus a train of such cars may be pushed progressively into a rotary tipple and the cars which are to be dumped by the turning of the tipple separated from each other by the disengagement of the hook, C^1 , in the manner above described. After the dumping of the first car or cars, the train may be pushed to bring the next succeeding car or cars into the tipple, the hook being still kept in the raised and clear position. Then the next car or cars are to be similarly detached from the next succeeding car and then dumped. This operation is to be repeated until all the cars of the entire train have been dumped. As soon as any cars have been dumped, their connection with preceding cars may be restored by releasing and lowering the appropriate hooks.

As an auxiliary means tending to hold the hook, C^1 , in the engaged position, Figs. 2 and 3 show an expanding coil spring, E,

placed horizontally into the lower part of the space between the walls, C², one end of said spring being secured to ears, E¹, on the hub, C⁴, of the hook and the other end of the spring being secured to ears, E², on the inner face of the wall, C³. When said spring is made a part of the structure, it yieldingly resists turning of the hub in the direction permitting the rising of the head

10 of the hook while the cars are being jolted.

By combining the rock shaft and the hook, the coupling can be operated by attendants without going between or reaching between the cars and being thereby exposed to danger of being injured when the cars are

15 pushed together or given an unexpected movement.

When the hook, C¹, has been released from the bumper, B, and the cars have been separated to avoid engagement between the hook and the bumper, B, and the rock shaft arm is not engaged to hold the hook in the elevated position, the body of the hook will rest on the wall, C³, and the lug, C⁷, of the bumper, C, whereby the head of the hook will be at the proper elevation to be lifted when the hook is thereafter pushed against a bumper, B.

It has already been mentioned that the hook may be turned into the elevated position and so held when the cars are to be turned in a rotary tipple. Placing the hook into the upright position to prevent automatic coupling when adjacent cars are pushed together is also desirable when cars are being switched or otherwise shifted and brought into engagement when it is not desired to couple.

I claim as my invention:

40 1. A mine car coupling structure comprising two bumpers, the first of said bumpers having an engaging face which is upright and extends transversely to the length of the car in a curved course in the below-mentioned plane, and a hook having a point and being hinged to the second of said bumpers on a horizontal axis and adapted to turn on said axis to move said point in an arc extending, when the first bumper is not in range, from below the horizontal plane of said hinge upward in an arc above said plane and above the height of said engaging face of the first bumper, whereby said point is adapted to engage said face in said plane and slide laterally along said face during changes in alignment of the cars which support said bumpers, substantially as described.

60 2. A mine car coupling structure comprising two bumpers, the first of said bumpers having an engaging face which is upright and extends transversely to the length of the car in a curved course in the below-mentioned plane, a hook having a point and being hinged to the second of said bumpers on

a horizontal axis and adapted to turn on said axis to move said point in an arc extending, when the first bumper is not in range, from below the horizontal plane of said hinge upward in an arc above said plane and above the height of said engaging face of the first bumper, whereby said point is adapted to engage said face in said plane and slide laterally along said face during changes in alignment of the cars which support said bumpers, and a spring tending to turn said hook downward, substantially as described.

3. A mine car coupling structure comprising two bumpers, the first of said bumpers having an engaging face which is upright and extends transversely to the length of the car in a curved course in the below-mentioned plane, a hook having a point and being hinged to the second of said bumpers on a horizontal axis and adapted to turn on said axis to move said point in an arc extending, when the first bumper is not in range, from below the horizontal plane of said hinge upward in an arc above said plane and above the height of said engaging face of the first bumper, whereby said point is adapted to engage said face in said plane and slide laterally along said face during changes in alignment of the cars which support said bumpers, and a spring tending to turn the hook downward, substantially as described.

4. A mine car coupling structure comprising two bumpers formed for engagement with each other in the below-mentioned plane, the first of said bumpers having an engaging face which is upright and extends transversely to the length of the car in a curved course in the below-mentioned plane, and a hook having a point and being hinged to the second of said bumpers on a horizontal axis and adapted to turn on said axis to move said point in an arc extending, when the first bumper is not in range, from below the horizontal plane of said hinge upward in an arc above said plane and above the height of said engaging face of the first bumper, whereby said point is adapted to engage said face in said plane and slide laterally along said face during changes in alignment of the cars which support said bumpers, substantially as described.

5. A mine car coupling structure comprising two bumpers, the first of said bumpers having an engaging face which is upright and extends transversely to the length of the car in a curved course in the below-mentioned plane, and a hook having a point and being hinged to the second of said bumpers on a horizontal axis and adapted to turn on said axis to move said point in an arc extending, when the first bumper is not in

- range, from below the horizontal plane of said hinge upward in an arc across a line extending upward from the outer face of the second bumper in the longitudinal upright plane of the car which supports the second bumper, and means for holding the hook and point in said raised position, whereby the cars bearing said bumpers may meet without coupling and whereby either of said cars may be turned independently of the other on its longitudinal axis in a rotary tipple, substantially as described.
6. A mine car coupling structure comprising two bumpers, the first of said bumpers having an engaging face which is upright and extends transversely to the length of the car in a curved course in the below-mentioned plane, and a hook having a point and being hinged to the second of said bumpers on a horizontal axis and adapted to turn on said axis to move said point in an arc extending, when the first bumper is not in range, from below the horizontal plane of said hinge upward in an arc across a line extending upward from the outer face of the second bumper in the longitudinal upright plane of the car which supports the second bumper, and means for holding the hook and point in said raised position, whereby the cars bearing said bumpers may meet without coupling and whereby either of said cars may be turned independently of the other on its longitudinal axis in a rotary tipple, and a spring tending to turn said hook downward, substantially as described.
7. A mine car coupling structure comprising two bumpers, the first of said bumpers having an engaging face which is upright and extends transversely to the length of the car in a curved course in the below-mentioned plane, and a hook having a point and being hinged to the second of said bumpers on a horizontal axis and adapted to turn on said axis to move said point in an arc ex-

tending, when the first bumper is not in range, from below the horizontal plane of said hinge upward in an arc across a line extending upward from the outer face of the second bumper in the longitudinal upright plane of the car which supports the second bumper, and means for holding the hook and point in said raised position, whereby the cars bearing said bumpers may meet without coupling and whereby either of said cars may be turned independently of the other on its longitudinal axis in a rotary tipple, and a spring located within the second bumper in operative relation with the hook to tend to turn the hook downward, substantially as described.

8. A mine car coupling structure comprising two bumpers, the first of said bumpers having an engaging face which is upright and extends transversely to the length of the car in a curved course in the below-mentioned plane, and a hook having a point and being hinged to the second of said bumpers on a horizontal axis and adapted to turn on said axis to move said point in an arc extending, when the first bumper is not in range, from below the horizontal plane of said hinge upward in an arc across a line extending upward from the outer face of the second bumper in the longitudinal upright plane of the car which supports the second bumper, and means for holding the hook and point in said raised position, whereby the cars bearing said bumpers may meet without coupling, and whereby either of said cars may be turned independently of the other on its longitudinal axis in a rotary tipple, and said bumpers being formed for engagement with each other in said plane, substantially as described.

In testimony whereof I have signed my name, this 20th day of March, in the year one thousand nine hundred and twenty-two.

HUGH W. SANFORD.
